US0D1065047S

(12) **United States Design Patent** (10) **Patent No.:** **US D1,065,047 S**
(45) **Date of Patent:** **** Mar. 4, 2025**

(54) **PORTABLE POWER STATION**

(71) Applicant: **ShenZhen YangZhe New Energy Technology Co., Ltd.**, Shenzhen (CN)

(72) Inventor: **Qiongbin Xie**, Shenzhen (CN)

(73) Assignee: **ShenZhen YangZhe New Energy Technology Co., Ltd.**, Shenzhen (CN)

(**) Term: **15 Years**

(21) Appl. No.: **29/860,999**

(22) Filed: **Nov. 24, 2022**

(51) LOC (15) Cl. **13-02**

(52) U.S. Cl.

USPC **D13/103**

(58) **Field of Classification Search**

(57) **CLAIM**

The ornamental design for a portable power station, as shown and described.

DESCRIPTION

FIG. 1 is a bottom perspective view of a portable power station, showing my new design;

FIG. 2 is a top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the portable power station, which form no part of the claimed design.
